UNITED STATES PATENT OFFICE.

JOSEPH A. LONG, OF EAST ORANGE, NEW JERSEY.

COMBINED GRATE AND ASH-SIFTER.

1,362,427.

Specification of Letters Patent. Patented Dec. 14, 1920.

Application filed January 16, 1920. Serial No. 351,754.

To all whom it may concern:

Be it known that I, JOSEPH A. LONG, a citizen of the United States, and a resident of East Orange, in the county of Essex and 5 State of New Jersey, have invented a new and Improved Combined Grate and Ash-Sifter, of which the following is a full, clear, and exact description.

This invention relates to stoves and furnaces and has particular reference to means 10 for sifting ashes by means applied beneath the grate and operated simultaneously with the shaking of the grate.

Among the objects of the invention therefore is to provide a construction including 15 a sifter for ashes located in the ash pit beneath the grate and having means associated with the grate controlling means to cause the sifting of the ashes and delivery of the 20 clinkers or unburned lumps of fuel forward of the ash pit whence they may be scooped up to be reburned or otherwise disposed of.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical longitudinal section 35 on the line 1—1 of Fig. 2.

Fig. 2 is a front elevation of the sifter, the furnace being shown diagrammatically.

Fig. 3 is a plan view of the sifter showing especially the relation of the pivot support 40 thereof to the main portion of the sifter.

Referring now more specifically to the drawings I show at 10 any suitable number, arrangement or design of grate bars indicated as being movable around pivots 11 45 and each having an arm 12 extending downward and having pivot connection at 13 with actuating means in the nature of a reciprocating bar 14 extending horizontally beneath the bars 10 and projecting in front of the 50 furnace where it is connected at 15 to a lever 16 having a link connection 17 with a fixed pivot point 18. An arm 16' is connected to the upper end of the lever for hand operation thereof and the shaking of 55 the grate. The parts thus far described are or may be of any suitable or conventional

construction, and *per se* are not my invention, the same being indicated however for the purpose of showing the arrangement and operation of my improvement.

60

Supported between the grate and the bottom of the furnace or the floor upon which it is erected and located on some suitable point back of the center of the ash pit 19 is a pivot rod 20 the same being shown as supported in holes 21 in the side walls of the ash pit. 22 indicates a sieve or ash sifter shown as constructed of an angle rail 23 and a screen or other reticulated body 24 of a mesh suitable for the ashes or finer particles 70 to pass through, but serving to prevent the passage therethrough of the unburned fuel or clinkers. The upwardly projecting flange of the angle member 23 is continuous along the back and side portions of the sifter, but 75 is discontinued at the front providing a discharge mouth 25 for those portions of the material that do not pass through the mesh. The front portion of the structure also includes two downwardly projecting feet 26 80 which in one position of the sifter are adapted to strike against the floor.

The pivot rod 20 is disposed at such an elevation within the ash pit as to hold the sifter in an inclined position when the feet 85 26 are in contact with the floor as shown in Fig. 1. At this time the rear portion of the sifter is near the level of the grate actuator 14.

Fixed rigidly to the rear portion of the 90 sifter is a standard 27 the same projecting upward substantially at a right angle to the reticulated body 24 and terminating in a slide hook 27' directed forward. This standard is shown fixed to the sifter at any suitable point adjacent to the center of the back portion of the angle member 23 and cooperating with the standard is a finger 28 carried by the grate bar actuator 14 and projecting horizontally therefrom. The 100 sifter is lifted to or toward its horizontal position as indicated in dotted lines in Fig. 1 by direct contact between the standard 27 and the finger 28 when the actuator 14 is moved rearward, and when the actuator is 105 moved forward the finger 28 tends to move forward away from the standard allowing the standard and sifter to tilt forward around the pivot 20 by reason of the preponderance of weight on that portion of the sifter in front of the rod 20. This forward movement of the actuator therefore 110

causes or permits the dropping of the sifter downward with the feet 26 coming into contact with the floor or bottom of the furnace with sufficient force to agitate the materials that may have been delivered upon the screen 24 from the grate, and such impact causes the sifting through the sifter of the smaller particles and the forward delivery of the heavier particles through the mouth 25 at the front of the furnace. A pan or tray of any suitable size or form may be provided beneath the sifter if desired in order to catch the ashes coming through the sifter, but if the pan or tray is not used the ashes can be removed from beneath the sifter by a shovel or the like in the usual manner. For the removal of the ashes by any means the sifter will be held elevated as shown in dotted lines in Fig. 1 by means of the movement of the actuator rearward.

The labor necessary for the actuation of the shaking lever is not materially increased by the provision of the sifter shown herein because the preponderance of weight in the front portion thereof is not important enough to require much force to swing the sifter toward its horizontal position. It will be appreciated therefore that the saving of time and convenience incident to the use of this sifter coincidentally with the normal shaking of the grate are of vast importance. It is well known that much coal or other useful fuel in a partially or imperfectly burned condition is wasted

along with the ashes and many householders hesitate to take steps to prevent this waste of fuel because of the inconvenience and dust that are occasioned by the sifting of ashes by the means usually provided for this purpose.

I claim:

1. The combination with a grate including a reciprocating bar and means to actuate the same to shake the grate, of an ash sifter located beneath the grate in position to receive the material from the grate, a pivot support for the sifter located at one side of the center of the sifter and constituting a fixed axis around which the sifter is adapted to oscillate, a standard fixed to the sifter and extending upward therefrom, and a finger fixed to the bar aforesaid and extending into coöperation with the standard whereby when the bar is reciprocated the sifter will be moved around its axis.

2. A device of the nature set forth in claim 1 in which the standard is provided with a hook at its upper end and the finger is so arranged as to wipe upward along the standard toward said hook when the shaker bar is reciprocated rearward.

3. A device of the nature set forth in claim 1 in which the standard and finger have loose coöoperative connection whereby when the shaker bar is moved forward the sifter may be free to drop and cause impact between the front end thereof and the floor of the ash pit.

JOSEPH A. LONG.
